UNITED STATES PATENT OFFICE.

PAUL L. PARSONS, OF BELVIDERE, ILLINOIS, ASSIGNOR TO PARSONS CASKET HARDWARE COMPANY, OF BELVIDERE, ILLINOIS, A CORPORATION OF ILLINOIS.

DESIGN FOR A CASKET-HANDLE EAR.

Application filed February 11, 1925. Serial No. 12,350. Term of patent 8½ years.

To all whom it may concern:

Be it known that I, PAUL L. PARSONS, a citizen of the United States, residing at Belvidere, in the county of Boone and the State of Illinois, have invented a new, original, and ornamental Design for Casket-Handle Ear, of which the following is a specification, reference being had to the accompanying drawing, forming part thereof.

The figure is a plan view of a casket handle-ear showing my new design.

I claim:

The ornamental design for a casket handle-ear, as shown.

PAUL L. PARSONS.
